UNITED STATES PATENT OFFICE.

MORRIS HERZBERG, OF WEST POINT, GEORGIA.

INKSTAND.

SPECIFICATION forming part of Letters Patent No. 308,157, dated November 18, 1884.

Application filed June 6, 1884. (No model.)

To all whom it may concern:

Be it known that I, MORRIS HERZBERG, of West Point, in the county of Troup and State of Georgia, have invented a new and Improved Inkstand, of which the following is a full, clear, and exact description.

This invention relates to that class of inkstands wherein provision is made to prevent rapid evaporation of the ink; and the invention consists in the construction and arrangement of parts, as will be hereinafter fully described and claimed.

Reference is to be had to the accompanying drawings, forming a part of this specification, in which similar letters of reference indicate corresponding parts in both the figures.

Figure 1 is a sectional elevation of my new and improved inkstand, and Fig. 2 is a sectional plan view of the same taken on the line 20 *xx* of Fig. 1.

A represents the body of the inkstand, formed with the ink-chamber *a*, and a bottom, *b*, of considerable thickness. The chamber *a* is covered at the top with the plate *c*, which is 25 formed with the central aperture, *d*. The bottom *b* has the central cavity, *e*, formed in it.

In the aperture *d* is fitted the internally-screw-threaded collar *f*, and in this collar and cavity *e* is fitted the tube *B*, the same being 30 held in place by the screw-threads *g*, formed at the top of the tube, engaging with the screw-threads of the collar *f*. By preference the tube *B* has formed integral with it at the top the flange *h*, which may be milled at its outer 35 edge to facilitate the removal of the tube *B* for cleaning or filling the chamber *a* with ink, and this flange *h* overlaps the collar *f*, so as to make a good finish at the top of the stand. The tube *B* has the apertures *i* formed 40 in it at or near the inner surface of the bottom *b*, and in the tube is placed the coiled spring *j* and the dip-cup *C*, which latter fits loosely in the tube, and rests upon the upper end of the spring *j*, as shown in Fig. 1, so 45 that the spring *j* normally holds the dip-cup elevated. The dip-cup *C* has attached to it the wires *k*, which are surrounded by the button *l*, by which the dip-cup may conveniently be depressed in the tube *B*, against the tension of the spring *j*, to or below the apertures 50

i, for filling it with ink from the ink-chamber *a*. At *m* the flange *h* is formed with an inwardly-projecting shoulder, and beneath this shoulder *m* is fitted the packing *o*, for forming a tight joint with the upper flange of the 55 dip-cup *C* when in elevated position.

In use, the chamber *a* being supplied with ink, the cup *C* will be filled by depressing it in the tube *B* to the openings *i* by pressure upon the button *l*. Owing to the cavity *e*, 60 the top of the cup may be lowered level with the bottom *b*, so that the cup may be filled when there is but a small quantity of ink in the chamber *a*. The cup *C* being filled and the pressure removed from the button *l*, the 65 spring *j* will elevate the cup *C* to the position shown in Fig. 1, and hold it there for dipping the pen. When in this elevated position, the cup *C*, by means of its outer flange resting against the packing *o*, closes the opening 70 to the inkstand, so that the main body of the ink is not exposed to the atmosphere, and thus prevents rapid evaporation of the ink. The cup *C*, when in this elevated position, also serves to limit the distance of the 75 insertion of the pen, so that there is no danger of covering the pen-holder with ink and getting the ink upon the fingers, and in case the inkstand should happen to get upset only the ink that may be in the dip-cup will be 80 spilled, as the main body of the ink will be kept in the stand by the cup *C*.

Although I have shown the body of the inkstand made entire of one piece of glass or metal, it will be understood that it may be 85 made of two or more pieces of glass or metal properly fitted together, if desired, and not depart from the spirit of my invention.

Having thus fully described my invention, I claim as new and desire to secure by Letters 90 Patent—

1. The combination, with the inkstand *A*, of the removable apertured tube *B*, a spring within said tube, and a vertically-reciprocating dip-cup resting on the spring within the 95 tube and provided with a handle, substantially as set forth.

2. The combination, with the inkstand provided with an internally-threaded collar, *f*, of tube *B*, screwing into said collar, spring *j* 100

within said tube, and the reciprocating dip-cup C, resting on spring j and provided with the handle k l, substantially as set forth.

3. The inkstand herein shown and described, consisting of the covered or closed body A, having cavity e formed in the bottom b, in combination with the apertured tube B, movable dip-cup C, and spring j, the cup C being

provided with wires k for depressing it in the tube, substantially as and for the purposes set forth.

MORRIS HERZBERG.
